HUGO STRACHE, OF VIENNA, AUSTRIA-HUNGARY.

METHOD OF PRODUCING COMBUSTIBLE GASES.

1,154,455.

Specification of Letters Patent.

Patented Sept. 21, 1915.

Application filed February 12, 1915. Serial No. 7,756.

To all whom it may concern:

Be it known that I, Dr. HUGO STRACHE, a subject of the Emperor of Austria-Hungary, and a resident of VI Theobaldgasse 15, Vienna, in the Empire of Austria-Hungary, have invented an Improved Method for Producing Combustible Gases; and I do hereby declare the following to be a full, clear, and exact description of the invention.

10 In the hitherto known methods of producing water gas and coal gas in one and the same apparatus, comprising a producer bearing a retort in its upper part, the coal gas produced in the upper part of the producer by hot blasting the lower part thereof, is obtained by a suitable adjusting of the closure members provided on the hot blast piping, discharge conduit and gas discharge conduit, the pressure between the exhaust 15 gases and the coal gas being balanced so that a circulation of the hot blast gases upwardly into the retort and a circulation in a downward direction of the coal gas produced in the retort, cannot take place. This 20 method has the drawback that with the slightest variation in pressure, a variation in the throttling must also take place which by means of an automatic controller can be effected in an imperfect manner only.

25 The present invention relates to the production of producer gas consisting of a mixture of coal gas and water gas in such a manner that during the major portion of the duration of the hot blasting the gas discharge from the distilling chamber (retort) is completely shut off and the dimensions of the space remaining free above the coal are selected in such a manner that the coal gas produced during the hot blasting operation, can accumulate therein. The coal gas is lighter than the hot blast gases (carbon monoxid, carbonic acid gas and nitrogen) and therefore accumulates in the upper part of the distilling chamber and would escape 30 from the lower part of the chamber into the heating conduits if the chamber and the space above it were filled only completely with coal gas. If the dimensions of these spaces are sufficiently large an escape of 35 coal gas is avoided. During the ensuing period of production of water gas, the coal gas accumulated in the chamber is forced into the system by the coming current of water gas and is thus obtained. When commencing hot blasting again, the chamber and the free space above it, are filled with

a mixture of coal gas and water gas. In order to obtain this mixture as well the gas exhaust valve in the upper chamber is left open during the first moment of the hot 40 blasting, and is closed when the valuable mixture of coal gas and water gas is forced from the chamber by the hot blast. During the subsequent period of hot blasting, the gases of the latter are again forced out by 45 the coal gas when the said valve is closed, as previously explained, and the cycle begins once more.

The drawing shows by way of example, the application of this method to a gas producer the same being represented in vertical 50 sectional elevation.

The producer is provided with a distilling chamber or retort 1 located in the upper part thereof and extending into a head 14 the discharge tube 15 of which is provided with a valve 16 and leads to the receptacle 3. The lower portion 4 of the producer is filled with coke and in the distilling chamber 1, located above, coal is located. An air blowing pipe 5 is arranged at the lower end of the producer and provided with a valve 7. By blowing air through the pipe 6 underneath the grate 5, the column of coke is heated until it glows, the produced carbon monoxid is burned by blowing additional air through the pipe 8 which is provided with a valve 9 and leads to an annular channel 8^a provided with slots 8^b. The combustion gases surround the distilling chamber 1 and escape from the space 13 through the pipe 10 and the open valve 10^a to the chimney.

11 is a steam-pipe and 12 are covers for the openings arranged at the lower end of the gas producer for the purpose of withdrawing the coke.

Above the coal there is a free space 2 which is gradually filled with the distillation products which drive the heavier combustion gases lying in the interstices between the coal in a downward direction so that the same also escape from the lower part of the distilling chamber 1 to the heating conduits. The dimensions of the free space above the coal and the dimensions of the distilling chamber are selected in such a manner that during the duration of the hot blasting, these chambers are filled with coal gas. The gas outlet valve 16 is closed during this period of hot blasting. Subsequently 110 the draft inlet valve 7 in the pipe 6 and the air valve 9 are closed and steam is admit-

ted through the pipe 11. The chimney valve 10^a is also closed and the gas outlet valve 16 opened. The water gas produced in the lower part of the producer, passes through 5 the distilling chamber and therefore displaces the distillation gases accumulated herein, which escape through the valve 16 and the receptacle 3 into the system. During this time, the distillation of the coal continues as it is still heated by the hot water gas. In the distilling chamber 1 and in the space 2 above the coal, there is, at the end of the gas period, a mixture of water gas and distillation gases (coal gas). When hot- 10 blasting again, the chimney valve 10^a and the draft inlet valves 7 and 9 are opened. The gas outlet valve 16 however still remains open until the water gas and the distillation gases are displaced from the distilling 15 chamber and from the space 2. This is ascertained by a test flame which is provided at 17 which goes out as soon as the combustion gases leave the chamber. At this moment, the valve 16 is closed so that the space 20 2 and the distilling chamber are filled again with fresh distillation gases, as explained hereinbefore in connection with the first hot-blasting. It is possible in this manner to obtain the distillation products of coal and the 25 water gas without the use of the mechanical devices such as regulators or the like, and thus with a continuous gasification of the coal a valuable gas (Dowson gas) is obtained. It is obvious that the dimensions of 30 the space 2 above the coal must be selected in accordance with the actual conditions, that is to say with the capacity of the retort 1, with the nature of the coal and with the duration of the blasting, in such a manner as to 35 40 avoid escape of the coal gas formed during hot blasting to the chimney.

Having now described my invention what I claim and desire to secure by Letters Patent is:

- 45 1. A method of producing a gas composed of distillation gases and water gas, consisting in consecutively producing coal distillation gases by hot blasting coal contained in a distilling chamber arranged in the generator, accumulating said distilling gases in the distilling chamber, forming water gas by steam blasting and displacing the said distillation gases by the water gas which is displaced by the combustion gases of the following hot blasting operation, substantially 50 55 as described.

2. A method of producing a gas composed

of distillation gases and water gas, said method consisting in producing coal distillation gases by hot blasting coal contained in a distilling chamber arranged in the generator, accumulating said distilling gases in the distilling chamber while the gas outlet valve from said chamber is closed, forming then water gas by steam blasting and displacing the said distillation gases by the water gas formed into the gas outlet piping which is at the time open and which during the following hot blasting operation is held open until the producer gas still contained in the distilling chamber is displaced by the combustion gases, substantially as described and for the purpose set forth.

3. A method of producing a gas composed of distillation gases and water gas, said method consisting in producing coal distillation gases by hot blasting coal contained in a distilling chamber arranged in the upper part of the generator, accumulating said distilling gases in the distilling chamber and in a free space of suitable dimensions arranged above the same while the gas outlet valve from said chamber and space is closed, opening the gas outlet valve and forming then water gas by steam blasting, driving thereby the said distillation gases into the outlet piping, and closing the valve of said piping in the next period of hot blasting until the producer gas contained in the distilling chamber is displaced by the combustion gases, substantially as described.

4. A method of producing gas, which consists in generating coal distillation gases by hot blasting, then generating water gases by steam blasting, and in accumulating the mixed gases in a closed chamber, and in driving the mixed gases out of the said chamber with the succeeding hot blast, until a test flame in connection with the discharge pipe will no longer burn.

5. A method of producing gas, which consists in consecutively producing coal distillation gases by hot blasting, and in forming water gas by steam blasting, and in displacing the mixed gases by the succeeding hot blasting, until a test flame in connection with the discharging gas no longer burns.

In testimony whereof I have signed my name to this specification in the presence of two subscribing witnesses.
